James J. McARDLE *INVENTOR.*
By Joseph A. Miller *ATTORNEYS.*

UNITED STATES PATENT OFFICE.

JAMES J. MCARDLE, OF PAWTUCKET, RHODE ISLAND.

STEAM ENGINE.

Application filed March 15, 1922. Serial No. 543,847.

To all whom it may concern:

Be it known that I, JAMES J. MCARDLE, a citizen of the United States, residing at Pawtucket, in the county of Providence and State of Rhode Island, have invented new and useful Improvements in Steam Engines, of which the following is a specification.

This invention relates to certain new and useful improvements in steam engines, and 10 the primary object thereof is to provide means for effecting quick opening and closing of the intake valves and to simultaneously and quickly effect opening and closing of the exhaust valves at the opposite end 15 of the cylinder upon each stroke of the piston, so as to thereby quickly relieve all possible back pressure on the piston when the steam enters the cylinder to effect operation of the piston.

20 A further object of the invention is to provide means for tripping the exhaust valves when the piston has completed its stroke and is about to commence its return stroke. The invention further aims to provide 25 an engine which has improved and simplified means for performing the above described operations of the valves.

Still further and other objects will be later set forth and manifested in the course 30 of the following description.

The invention more specifically, resides in the combination of parts and the construction thereof as will be now fully set forth.

In the drawings:—

35 Figure 1 is a top plan view of a steam engine constructed in accordance with the present invention;

Figure 2 is a side elevation;

40 Figure 3 is an enlarged detail side elevation.

In proceeding in accordance with the present invention a pair of gears 1 and 2 are eccentrically mounted on the main drive shaft 3 of the engine and are in mesh with 45 similar gears 4 and 5 respectively mounted on an arbor or stub shaft 6. Rockers 7 and 8 are pivoted at their lower ends to a pin 9 which latter is suitably secured to the base 10, rods 11 and 12 being pivoted to the 50 respective rockers and to the respective gears 4 and 5. The rockers are further connected by means of rods 13 and 14 respectively to wrist plates 15 and 16, the wrist plates being arranged one to the rear of the other and 55 in register, and being loosely mounted on an arbor 17. The steam chest is designated 18,

the cross-head guide 19 and the piston rod 20, the latter connected to the crank 21 of the main drive shaft 3.

The several inlet and exhaust valves are 60 operated by means now to be described. The inlet valves 22' and 22'' have arms 22 connected thereto, the latter being of a bell crank type, which are tensioned by rods 23 to which springs 24 are connected, the 65 springs in turn being secured to the base 10. A pair of latches 25 and 25' are pivoted at 26 and 26' to the respective wrist plates 15 and 16. The lower ends of the arms 22 are provided with pins 27 and 28' upon which 70 latter the outer ends of the latches 25 and 25' rest. The under faces of the latches are formed with cams 28 and 29 and with stops 30 and 31. Cam trips 32 and 33 are rigidly secured to the steam chest and engage the 75 cams 28 and 29 to thereby effect operation of the latches 25 and 25'. The exhaust valves 34 and 35 have arms 36 and 37 connected thereto, the arms carrying pins 38 and 39 and having slotted outer ends 40 and 41 in 80 which pins 42 carried by spring tensioned rods 43 and 43' are mounted. The rods 43 slide in brackets 44 mounted on the steam chest, and the springs act to normally move the arms 36 and 37 outwardly to their vertical position. Latches 45 and 46 are pivoted at their inner ends to the respective wrist plates 16 and 15 and are provided with stop shoulders 47 and 48 and with cams 49 and 50, the latter being for engagement 85 with stationary cam trips 51 and 52 which may be suitably secured to the base 10. The outer ends of the latches 45 and 46 are guided in slots provided therefore in standards 53 and 54 that are suitably secured to 90 the base 10.

In operation, the wrist plates are operated by the rockers through the gear connections as described, the intake valve 22'' being operated by virtue of the shoulder 31 of the latch 25' striking pin 28', the latch being moved by the wrist plate in the direction of the arrow of Figure 3. Both intake latches move in the same direction. At the same time latch 25 due to the slowing down of 105 the gear 5 is moving into position for engagement of its shoulder 30 with the pin 27. At the same time that latch 25' is operating the valve 22'' the shoulder 47 of latch 45 is engaging pin 38 to open the 110 exhaust valve 34, the latter being given a very quick movement since it is being op-

erated from the wrist plate 16, which latter is also operating the intake valve 22". When the piston has completed its movement, then the latch 45 is tripped by cam 51, releasing pin 38 from stop 47 whereupon the spring of rod 43' suddenly expanding forces the arm 36 and thereby valve 34 into closed position. The above cycle of operation is repeated by the operation of the 10 opposite set of valves 22' and 35 in the manner described in connection with the first set. The springs 24 connected to the rods 23 serve to quickly move the intake valves 22' and 22" to closed position, as in 15 the instance of the spring pressed rods 43' and 43 effecting similar quick movement of the exhaust valves 34 and 35.

Having thus described my invention, what I claim as new and desire to secure by Letters Patent is:—

1. In a steam engine, a cylinder having an inlet and an exhaust valve at each end thereof, a pair of wrist plates pivoted between their ends at points between the said 25 pairs of valves at the ends of the cylinder, oppositely extending latches pivoted to the wrist plates and each having a stop shoulder and a cam thereon, there being a latch for each valve, spring pressed bell cranks 30 connected to the intake valves and having pins engageable with the stop shoulders to allow the latches to open the intake valves, cam trips for the latches to operate the latter to effect disengagement of the shoulders from the pins, slotted arms connected to the exhaust valves, and having pins to engage the stop shoulders of the latches thereof, spring pressed rods having pins engaged in the slots of the slotted arms for effecting 35 closing of the exhaust valves, rockers, rods pivoted to the rockers and to the wrist plates, pairs of intermeshing eccentric gears actuated by the engine drive shaft, and rods pivoted to the gears and to the rockers.
2. In a steam engine, a cylinder having an inlet and an exhaust valve at each end thereof, a pair of wrist plates pivoted between their ends at points between the said 50 pairs of valves at the ends of the cylinder, oppositely extending latches pivoted to the wrist plates and each having a stop shoulder and a cam thereon, there being a latch for each valve, spring pressed bell cranks connected to the intake valves and having pins engageable with the stop shoulders to allow the latches to open the intake valves, cam trips for the latches to operate the latter to effect disengagement of the pins from the shoulders, slotted arms connected 55 to the exhaust valves, and having pins to

engage the stop shoulders of the latches thereof, spring pressed rods having pins engaged in the slots of the slotted arms for effecting closing of the exhaust valves, and means operated by the engine drive shaft 65 to actuate the wrist plates.

3. In a steam engine, a cylinder having an inlet and an exhaust valve at each end thereof, a pair of wrist plates pivoted between their ends at points between the said 70 pairs of valves at the ends of the cylinder, a latch for each valve pivoted to the wrist plates and each having a stop and a cam thereon, spring pressed bell cranks connected to the intake valves and having pins 75 engageable with the stops to allow the latches to open the intake valves, cam trips for the latches to operate the latter to effect disengagement of the stops from the pins, arms connected to the exhaust valves and 80 having pins engaging the stops, spring devices for actuating the arms to close the exhaust valves, and means operated by the engine drive shaft to actuate the wrist plates.

4. In a steam engine valve operating 85 mechanism, a bell-crank lever connected to one of the valves and having a vertically and a horizontally disposed arm, a pin carried by the vertical arm of the lever, a spring connected to the horizontal arm of the lever, 90 operating means, a horizontal latch pivoted at one end to the operating means and having its opposite end slidably supported on the pin, the latch having a cam face and a shoulder, the latter engageable with the pin, 95 and a cam engageable with the cam face of the latch to raise the shoulder thereof up out of engagement with the pin.

5. In a steam engine valve operating 100 mechanism, an arm connected adjacent one end to one of the valves and extending upwardly therefrom, a slidable spring pressed rod having a pin and slot connection with the opposite free end of the arm, a pin on the arm between its ends, a horizontal latch having a stop engageable with the pin, means pivotally connected to the inner end of the latch to actuate the latter from the engine drive shaft, cam means to 105 actuate the latch to disengage the stop thereof from the pin, and means to slidably support the outer end of the latch.

In testimony whereof I have signed my name to this specification in the presence of two subscribing witnesses.

JAMES J. McARDLE.
